(57) **CLAIM**

The ornamental design for a pelvic educational model, as shown and described.

DESCRIPTION

FIG. 1 is a perspective view of the pelvic educational model, in accordance with the new design;

FIG. 2 is a front view thereof, viewed parallel to the slope of the stand;

FIG. 3 is a back view thereof;

FIG. 4 is a left-side view thereof;

FIG. 5 is a right-side view thereof;

FIG. 6 is a top view thereof, viewed down the slope of the stand;

FIG. 7 is a bottom view thereof, viewed up the slope of the stand;

FIG. 8 is a left-side view of the pelvic educational model without the stand for illustrative clarity;

FIG. 9 is top view thereof, without the stand;

FIG. 10 is a front view of the stand, viewed perpendicular to the slope of the stand without the pelvic educational model for illustrative clarity; and,

FIG. 11 is a left-side view of the stand thereof.

The broken lines in the drawings depict portions of the pelvic educational model that form no part of the claimed design.

1 Claim, 11 Drawing Sheets
